Walter E. Moore, Bel Nor, Mo., assignor to Swing-A-Way Manufacturing Company, St. Louis, Mo., a corporation of Missouri

Application August 1, 1955, Serial No. 37,247

Term of patent 14 years

(Cl. D89—1)

Figure 1 is a top plan view of a portable ice crusher casing showing my new design;

Figure 2 is a side elevational view thereof;

Figure 3 is a side elevational view thereof, looking at the other side;

Figure 4 is a front elevational view thereof; and

Figure 5 is a bottom plan view thereof.

The undisclosed rear of my portable ice crusher casing is identical with the front disclosure in Figure 4.

I claim:

The ornamental design for a portable ice crusher casing, as shown.
